UNITED STATES PATENT OFFICE.

ALBERT N. OTIS, OF SCHENECTADY, NEW YORK, ASSIGNOR TO GENERAL ELECTRIC COMPANY, A CORPORATION OF NEW YORK.

TEMPERATURE-CONTROLLER.

1,353,665.

Specification of Letters Patent. Patented Sept. 21, 1920.

Application filed July 18, 1918. Serial No. 245,457.

To all whom it may concern:

Be it known that I, ALBERT N. OTIS, a citizen of the United States, residing at Schenectady, in the county of Schenectady, State of New York, have invented certain new and useful Improvements in Temperature-Controllers, of which the following is a specification.

My invention relates to improvements in the control of electric heating apparatus, and has reference more specifically to apparatus for melting pots of the kind used on typesetting machines and the like.

The melting pot of a typesetting machine is supported on a movable frame which is subject to quick or abrupt movement. As ordinarily constructed, the arrangement of the thermostat for controlling the electric heating units of a melting pot has been such that it was affected by this pot movement so as to cause chattering at the contacts. One of the objects of my invention is to provide an improved arrangement whereby the movement of the pot will not detrimentally affect the contacts. Another object of my invention is to so arrange the thermostat that it will not be subject to the strains which have heretofore been placed upon the thermostat by reason of the contraction of the metal in cooling. Other objects and purposes of my invention will appear in the course of the following specification in which I have shown my invention embodied in concrete form for purposes of illustration.

In the accompanying drawings illustrating my invention, Figure 1 is a side elevation of a melting pot embodying my invention with a portion broken away; Fig. 2 is a front elevation of the same; Fig. 3 shows a detail of the mounting of the thermostatic device; Fig. 4 is a sectional view of the thermostat; Fig. 5 is a sectional view taken at right angles to Fig. 4; Fig. 6 is a diagram showing the circuit connections.

Referring to the drawings, 1 represents the melting pot of a typesetting machine which is heated by an electric heating unit A (Fig. 6). This melting pot is of standard construction and, inasmuch as it forms no part of my invention, it need not be described in detail. It is sufficient, therefore, to state that the pot is pivotally mounted to rotate through a small angle on the shaft 2 as indicated in full and dotted lines respectively. The thermostatic device which is

mounted on the top of this pot is shown in detail in Figs. 4 and 5. This thermostatic device comprises a casing 3 which incloses the switch mechanism and a frame 4 secured to the bottom of this casing for supporting a thermostatic element 5. This thermostatic element and supporting frame are adapted to enter the metal of the pot, while the switch portion extends above, as shown in Figs. 1 and 2. The thermostatic element projects upward into the switch casing and terminates in a reduced portion 6 which engages the switch mechanism to cause the movement of the latter. The switch mechanism proper consists of a frame 7 pivoted on ball bearing pivots 8 so as to give practically a frictionless movement in response to the expansion of the thermostatic element. The expansion of the thermostatic element causes a movement of this frame on its pivot by engaging an eccentric 9 mounted on a shaft 10 carried by the frame. The engagement between the thermostatic element and the switch element is made in the form of an eccentric for the purpose of furnishing temperature adjustment. The eccentric is turned on its axis to give the adjustment by means of a worm 11 engaging the worm wheel 12 mounted upon the shaft 10.

Secured to the movable frame 7 is a switch arm 13 which projects upward between two fixed contacts 14 and 15. The switch arm 13 has two contacts, one of which 16 cooperates with fixed contact 14 and the other 17 with fixed contact 15. Exterior terminals 18 and 19 are provided for the fixed contacts 14 and 15 respectively. This switch arm is caused to normally occupy the position against the contact 14 shown in the drawing by means of a spring 20. By referring to Fig. 4 it will be noted that the pivotal point of the movable frame which carries the switch arm is very slightly out of the center line of the thermostatic element. The eccentric 9 is located in the center line, while the pivotal point of the frame is slightly to the left of this line. This slight off-set from the center represents the leverage at which the thermostatic member acts upon the switch member and is made very small because the expansion of the thermostatic element is slight. The switch member 13, however, is located some distance from the pivotal point of the frame, 110

and the switch member itself is relatively long so as to give a relatively large movement at the contacts as compared to the actual expansion of the thermostatic element.

It will be observed that with this arrangement the movement of the contacts is in a plane at right angles to the plane of movement of the melting pot, so that any abrupt movement of the melting pot will not cause movement of the contacts on the switch arm with reference to the stationary contacts. The contacts 16 and 17 are spring mounted by means of the spring strips 21 and 22 so as to make a good contact, and were it not for the fact that movement of the contact is at right angles to the movement of the pot, the abrupt movement of the pot would affect the contacts. As arranged, however, this difficulty does not occur.

One of the important features of my invention is in the mounting of the thermostatic mechanism upon the melting pot. As heretofore arranged, this mounting of the thermostat upon the pot has been made rigid. This has at times caused trouble by reason of the contraction strains put upon the thermostatic element by the solidifying of the metal to the pot. In order to overcome this difficulty, I have made the connection between the thermostatic mechanism and the pot resilient. In the arrangement shown in the drawings I have provided two bow springs 23 and 24 secured to the bottom of the casing. These springs bear upon the top of the pot, and screws 25 and 26, which loosely pass through the bottom of the switch casing, are screwed in the top of the pot so as to keep the bow springs slightly under strain. It will also be observed that springs 23 and 24 are mounted for movement in the plane of movement of the melting pot. The result is that the thermostatic mechanism, including the thermostatic element, may yield slightly as a whole, and the strains on the mechanism are thereby overcome.

In Fig. 6 I have shown a diagram of the circuit connections which I employ. Referring to this drawing, A represents the heating unit, the circuit of which is controlled by the switch member 13 through the thermostatic member 5. Instead of controlling the circuit of the heating element directly, the control is brought about by a relay consisting of two solenoids 27 and 28, one of which is connected to the stationary thermostatic contact 14, while the other is connected to the stationary contact 15. The arrangement is such that the circuit is never opened at the thermostatic contacts, but opened at the contacts 29 and 30 by the movable switch arm 31 operated in opposite directions by the solenoids 27 and 28 respectively.

In Fig. 6 the parts are shown in a position in which the heating unit is energized from the positive side of the line through the switch member 31, the contact 29 and the conductor 32 to the negative side of the line. This connection has been brought about by the energization of the solenoid 27 through the engagement of the thermostatic switch member 13 with stationary contact 14. As soon as the solenoid 27 started to move switch member 31 to contact 29, the circuit of solenoid 27 was opened at contact 30. Assuming that the temperature of the melting pot has reached a point where the circuit should be opened, the switch 13 will now be moved over to engagement with the fixed contact 15, thereby energizing solenoid 28 from the positive side of the line, switch member 31, contact 29, solenoid 28 and thermostatic contact 15 to the negative side of the line. This will cause the switch member 31 to be moved over to engagement with the contact 30, thereby opening the heater circuit, and at the same time partially closing the circuit of solenoid 27. The result is that the circuit is never broken at the thermostatic contacts, but at the contacts 29 and 30, and the switch member 31 will have sufficient movement and give a quick break such as is required. The thermostatic contacts merely complete the circuit for operating solenoids.

It will be seen that I have devised a thermostatic switch arrangement which is rugged and well adapted for use on melting pots used for melting linotype metal and the like, since the movement of the melting pot and the solidifying of the metal will not have any detrimental effect upon the thermostat.

While I have described my invention as embodied in concrete form and as operating in a specific manner in accordance with the provisions of the patent statutes, it should be understood that I do not limit my invention thereto, since various modifications thereof will suggest themselves to those skilled in the art without departing from the spirit of my invention, the scope of which is set forth in the annexed claims.

What I claim as new and desire to secure by Letters Patent of the United States, is:—

1. The combination with an electrically heated melting pot mounted for movement in a definite plane and a thermostatic device for controlling the temperature of the pot mounted thereon, and having a thermostatic element projecting into the pot and an external switch element operated by the thermostatic element in a plane perpendicular to the plane of movement of the pot.

2. The combination with an electrically heated melting pot and a thermostatic device for controlling the temperature of the pot resiliently mounted thereon, and how-

ing a thermostatic element projecting into the pot and an external switch element operated by the thermostatic element.

3. The combination with an electrically heated melting pot mounted for movement in a definite plane and a thermostatic device for controlling the temperature of the pot resiliently mounted for movement in the plane of movement of the pot, and having a 10 thermostatic element projecting into the pot and an external switch element operated by the thermostatic element.

4. The combination with an electrically heated pivoted melting pot, of a thermostatic device resiliently mounted thereon comprising a pivoted frame, an elongated switch member secured to the frame, an eccentric adjustably mounted in said frame and slightly out of the pivotal axis of the 20 frame, and a thermostatic element projecting into the pot and engaging the eccentric to cause a movement of the frame on its axis.

5. The combination with an electrically heated melting pot mounted for movement in a definite plane and a thermostatic device for controlling the temperature of the pot mounted thereon comprising a frame 25

pivoted for movement in a plane perpendicular to the plane of movement of the pot, 30 an elongated switch member mounted thereon, an eccentric adjustably mounted in said frame and slightly out of its pivotal axis, and a thermostatic element projecting into the pot and engaging the eccentric to cause 35 the frame to turn on its axis.

6. The combination with an electrically heated melting pot mounted for movement in a definite plane and a thermostatic device for controlling the temperature of the pot 40 mounted thereon comprising a casing resiliently mounted on the pot for movement in the plane of movement of the pot, a frame pivoted in said casing for movement in a plane perpendicular to the plane of movement of the pot, an elongated switch member mounted on said frame, an eccentric adjustably mounted in said frame and slightly out of its pivotal axis and a thermostatic element projecting into the pot and engaging the 45 eccentric to cause the frame to turn on its axis.

In witness whereof I have hereunto set my hand this 17th day of July, 1918.

ALBERT N. OTIS.
